UNITED STATES PATENT OFFICE.

GILBERT E. FERRY, OF DUNDEE, NEBRASKA.

CORNER-PIECE FOR WINDOW-SCREENS.

No. 914,126.

Specification of Letters Patent.

Patented March 2, 1909.

Application filed June 15, 1907. Serial No. 379,171.

To all whom it may concern:

Be it known that I, GILBERT E. FERRY, a citizen of the United States, residing at Dundee, in the county of Douglas and State of 5 Nebraska, have invented certain new and useful Improvements in Corner-Pieces for Window-Screens, of which the following is a specification.

This invention relates to window screen 10 corners, and has for its object to provide a simple, inexpensive, durable and efficient device of this character which will be effective for the purpose designed.

Further objects and advantages of this invention will appear in the following specification and the novel features thereof will be finally pointed out in the appended claims.

Referring to the accompanying drawings forming a part of this specification, wherein 20 like characters of reference denote similar parts throughout the several views:—Figure 1, is a detail showing one corner of a window frame constructed in accordance with my invention. Fig. 2, is a top view thereof. Fig. 25 3, is a perspective view of my improved corner with portions thereof broken away. Fig. 4, is also a perspective view thereof looking in the opposite direction. Fig. 5, is a plan view of the blank from which the corners are 30 formed.

Referring to the Fig. 5, of the drawings the reference character 1, designates a piece of sheet metal, cut in the proper form, ready to be bent to make one of the corners of my 35 proved frame. This sheet when cut in the proper form is T-shaped as clearly shown and has one edge recessed or cut-away as at 2, and has inner corners slit as at 3. To bend this blank into form of corner shown in Figs. 40 1, 2, 3, and 4, the edges 4, 5, 6, 7, 8, and 9, are bent at right angles to the face of the sheet as clearly shown in Figs. 2 and 4, and after this has been done the right angular sides 10, and 11, are bent upward on dotted lines 12, to 45 form a corner as clearly shown in Fig. 3, having the solid back 13, provided with the recess 2. Now, in order to set up or construct a frame, all that is necessary is to secure suitable frame members 14, and to insert the 50 ends thereof into the sockets 15 and 16, of the corner as shown in dotted lines in Fig. 4. After this has been done the wire cloth 16, is placed upon the frame as shown in Fig. 1, and a molding 17, secured to the frame as clearly 55 shown in Fig. 3, which molding serves to cover the edges of the wire cloth over which

they are tacked and to give a finish to the face of the frame.

The right angular face 11, of the corner, it will be observed, is provided with a plurality of slotted openings or apertures 18, through which the tacks are adapted to pass which hold the wire cloth to the frame. The faces 10 and 11, are each provided with the openings 19, through which the fastening 60 devices 20, such as nails, screws or the like are adapted to pass for firmly holding the frame section in the sockets 15 and 16.

It will be observed that the side frame members 14, are longitudinally grooved as 70 at 21, or otherwise suitably formed on their outer edges to receive the usual guides or rails 22, in the window frame, on which the screen can be slid up and down.

It will be readily seen that a frame constructed with my improved corners will be inexpensive, easily made, readily put together and when once put together will be perfectly square cornered, strong and durable. 75

Having fully described my invention, what I claim is:—

1. In combination with two right angular members of a frame the vertical one of which has a side groove, of a corner piece 80 therefor composed of a piece of sheet metal of L shape having a back engaging the outer edge of the horizontal of said members with a recess at one end of the back to register with said groove of the vertical member, parallel horizontal sides integral with the back having their edges turned inwardly and spaced apart and engaging the inner face of said horizontal member, vertical parallel portions integral with said back and having 85 their inner and outer free edges turned inwardly toward one another to engage said vertical member, the side edge extremities of the outer edges of the vertical portion terminating flush with said grooves. 90

2. In combination with two right angular members of a frame the vertical one of which has a side groove of a corner piece 95 therefor composed of a piece of sheet metal of L shape having a back engaging the outer edge of the horizontal of said members with a recess at one end of the back to register with said groove of the vertical member, parallel horizontal sides integral with the back having their edges turned inwardly and spaced apart and engaging the inner face of 100 said horizontal member, vertical parallel 105 portions integral with said back and having their inner and outer free edges turned inwardly toward one another to engage said vertical member, the side edge extremities of the outer edges of the vertical portion terminating flush with said grooves. 110

- portions integral with said back and having their inner and outer free edges turned inwardly toward one another to engage said vertical member, the side edge extremities of the outer edges of the vertical portion terminating flush with said groove, said horizontal sides and vertical portions being provided with openings, fastening extending through said openings and into said frame members, there being other openings in one of said horizontal sides and vertical portions, wire fabric secured to said sides and vertical portions, and molding secured to said wire fabric.
3. In combination with two right angular members of a frame, the vertical one of which has a groove in its outer side, a corner

piece of L-shape having three pairs of free edges the members of each pair being turned inwardly toward each other to embrace the side edges of said members, the inturned edges of the vertical part of the corner piece having their extremities terminating flush with said groove to strengthen the material of the vertical frame member on each side 25 of the groove thereof.

In testimony whereof I have signed my name to the specification in the presence of two subscribing witnesses.

GILBERT E. FERRY.
